US00D949690S

(12) **United States Design Patent** (10) Patent No.: **US D949,690 S**
(45) Date of Patent: **** Apr. 26, 2022**

(54) **CLOSURE FOR A CONTAINER**(71) Applicant: **H.J. Heinz Company Brands LLC**,
Pittsburgh, PA (US)(72) Inventors: **Balint Hiltser**, Lent (NL); **Guus Lueb**,
Bennekom (NL)(73) Assignee: **H.J. Heinz Company Brands LLC**,
Pittsburgh, PA (US)(**) Term: **15 Years**(21) Appl. No.: **29/737,015**(22) Filed: **Jun. 4, 2020****Related U.S. Application Data**

(62) Division of application No. 29/674,603, filed on Dec. 21, 2018, now Pat. No. Des. 889,260.

(51) LOC (13) Cl. **09-07**

(57) CLAIM

The ornamental design for a closure for a container, as shown and described.

DESCRIPTION

FIG. 1 is a top perspective view of a closure for a container in accordance with our new design in a closed configuration; FIG. 2 is a front elevation view thereof; FIG. 3 is a rear elevation view thereof; FIG. 4 is a left side elevation view thereof, the right side elevation view being a mirror image thereof; FIG. 5 is a top plan view thereof; FIG. 6 is a bottom plan view thereof; FIG. 7 is a top perspective view of the closure of FIGS. 1-6 in an open configuration; FIG. 8 is a front elevation view thereof; FIG. 9 is a rear elevation view thereof; FIG. 10 is a right side elevation view thereof, the left side elevation view being a mirror image thereof; FIG. 11 is a top plan view thereof; and, FIG. 12 is a bottom plan view thereof.

The broken lines depict portions of the closure that form no part of the claimed design.
